UNITED STATES PATENT OFFICE

2,457,095

RHEOSTAT WITH RECTILINEAR SLIDE

Fred P. Strother, Minneapolis, Minn., assignor to
 Minneapolis-Honeywell Regulator Company,
 Minneapolis, Minn., a corporation of Delaware

Application December 26, 1944, Serial No. 569,693

7 Claims. (Cl. 201—48)

1

This invention relates to an improved gyroscope erecting and levelling apparatus and has for one of its principal objects the concurrent and selective delivery of electric energy from a common source through a plurality of parallel circuits to operating members. The energy delivered through each parallel circuit or leg thereof may be selectively adjusted relative to the energy delivered through each other circuit or leg.

In the improved apparatus of this invention, electric energy from a common source may be passed through a plurality of parallel circuits, in which adjustable resistors are positioned, to energize a like plurality of operable members. The adjustable resistors may be arranged to deliver energy to the operable members throughout wide ranges so that operation of the members may be similar or may vary considerably in relation to each other. Moreover, the apparatus is so arranged that energy may be delivered to operate the members at a high or low speed without altering or changing the settings of the resistors. Additionally, the ratio of operation of the members at high speed is not necessarily the same as the ratio of operation of the members at low speed.

The improved control apparatus of this invention may be used in conjunction with various kinds of members operated in pairs or equipment operated by the application of forces from more than one direction wherein the force delivered to one member or from one direction may differ from the force delivered to the other member or from another direction. The present control apparatus is especially adapted to be used to operate the erecting or levelling mechanism of gyroscopes. However, its use is by no means confined to such employment. As illustrative of the adaptability and one of the uses of the improved apparatus it is herein shown and described in conjunction with the method and means for stabilizing gyro devices disclosed in my co-pending application, Serial No. 482,217, filed April 7, 1943, which issued as Patent No. 2,417,573 on March 18, 1947.

It is understood that any body rotating, particularly at a fairly high angular velocity, about an axis tends to resist motion of that axis in any direction other than parallel to itself. The application of a force to the axis of the gyroscope tending to rotate it out of this position causes a phenomenon known as precession of the gyroscope, that is, it effects a rotation of the axis of the gyroscope not in the plane of action of the force, but in a plane at an angle of 90 degrees with the plane of action of the force, the angle being measured in the direction of rotation of the gyroscope.

50

65

Another object of advantage and importance of the apparatus of this invention resides in the provision of means for applying a given force to a movable member in one direction and a different force to the same member from another direction.

A still further object of the invention is to pro-

5 10 15 20 25 30 35 40 45

In my co-pending application, the axis of rotation of the gyroscope is maintained in or moved toward its position of orientation by the operation of electromagnetic means. The electromagnetic means comprises two sets of elements positioned to rotate on axes at right angles to each other and normal to the axis of rotation of the gyroscope. Thus, when the axis of rotation of the gyro moves from its plane of orientation and from the plane of either of the right angle axes, two forces are required to right the gyroscope. If the electromagnetic elements rotate on equal radii then equal input in each electromagnetic element will result in equal forces applied to different sides of the gyroscope axis. However, the construction of a gyroscope having electromagnetic elements positioned to operate on precisely equal radii would not only entail slow, high precision work, but would also be extremely costly. The present structure solves this problem by the arrangement of resistors in each circuit which may be selectively adjusted so that the forces exerted against the axis of the gyroscope may be precisely equal although there may be considerable difference in the energy applied to and the moment of the electromagnetic elements. Additionally, the device may be set so that control or recovery in one direction is at a selectively different rate than control or recovery movement in the other direction.

In the operation of gyro stabilizing or levelling devices, especially those used in the control and operation of planes and aviation equipment, it is at times desirous and advantageous to make corrections and alter settings at a rapid rate and at other times to make the same corrections and alterations at a much slower rate. For instance, at the beginning of a bombing run, it is essential that the bombardier complete the setting of the gyro on a given course and range at the earliest possible moment. Accordingly, high speed responsive mechanism is here desirable and essential. However, after the course and range have been set the high speed mechanism could tend to cause overcontrol and result in the ship proceeding on an erratic course. Accordingly, low speed responsive mechanism is now desirable and essential to prevent overcorrection and overcontrol. The improved apparatus of this invention provides for both high and low speed operation.

vide means tending to maintain a movable member in a given position of orientation and for urging that member toward the given position at selectively different rates of speeds when the member is moved from its original position.

Additional objects of importance and advantage will become apparent as the following detailed description progresses, reference being had to the accompanying drawing wherein

Figure 1 is a front elevational view of an electrical unit which embodies the invention;

Figure 2 is a side elevational view thereof;

Figure 3 is an elevational view of the device shown in Figure 1 with the cover removed and portions thereof broken away;

Figure 4 is a vertical section taken on line 4-4 of Figure 3 looking in the direction indicated by the arrows;

Figure 5 is a slightly enlarged view of a fragmental portion of the structure shown in Figure 3. The switch is here shown in off position.

Figure 6 is a side elevation of the structure shown in Figure 5;

Figure 7 is similar to Figure 6 but shows the switch in high position; and

Figure 8 is a schematic wiring diagram showing the electrical circuits and operable positions of the control switch.

The reference number 10 indicates generally a casing comprising a base 11, a back-plate 12, and a cover 13. The parts may be secured together in any suitable manner as for instance by screws 14. The cover 13 is drilled to receive a shaft 16 upon which is mounted an operating handle 17. Abutment members 18 formed on the surface of the cover 13 provide stops to limit the rotational movement of the handle 17. The handle 17 is operably movable to off, low and high positions.

Journalized in the plate 12, in alignment with the shaft 16, is a shaft 19. Formed on the inwardly projecting end of the shaft 19 and rotatable therewith is a cam 23. Peripheral portions of the cam 23 on opposed sides thereof are turned axially of the shaft 19 to provide operating bosses 24. The bosses 24 are adapted to cooperate with portions of the shaft 16 to form a releasable driving connection between the handle 17 and the cam 23. Projecting radially from the cam 23 and spaced one from the other are two fingers 25 to which a flat insulating member 26 is secured. From the foregoing it will be apparent that rotation of the handle 17 and shaft 16 rotates the shaft 19 and cam 23 together with fingers 25 and the insulating member 26 within operating limits defined by abutment members 18. Secured to the insulating member 26 at a point intermediate the fingers 25 and electrically insulated therefrom is an elongated contact member 27. The contact member 27 is adapted to rotate with the cam assembly for a purpose hereinafter more fully disclosed.

Formed in the peripheral edge of the cam 23 are two low dwells 27 spaced one from the other, which are adapted to cooperate with a leaf spring 28 to maintain the cam 23 and associated parts in off and low positions. Extending outwardly from the peripheral edge of the cam 23 and turned at right angles thereto to engage a biasing spring 32 is an abutment 33. The abutment 33 and biasing spring 32 cooperate to load the cam when it is moved to high position and tends to urge it toward low position. Accordingly, when the handle 17 is released while in high position it will automatically return to low position. A stop member 34 is positioned in the path of travel

of the biasing spring 32 to prevent that member from urging the cam 23 beyond low position.

Secured to the plate 12, in any suitable manner as for instance by screws 35, is an insulating and supporting block 36. The supporting block 36 carries a plurality of conductor blades 37, 38, 41, and 42 which are spaced and insulated one from another. The blades 37, 38, 41, and 42 are electrically connected to a source of supply and 10 resistance members as will hereinafter more fully appear. Secured to the free end of the blade conductors 37 and 38 and slidably engaging the flat insulating member 26 are contacts 43 and 44, respectively. The contacts 43 and 44 are of considerable length and are adapted to maintain the free ends of the blade connectors 37 and 38 spaced from the blade connectors 41 and 42, as is best shown in Figures 4 and 5. Secured to the free ends of the blade connectors 41 and 42 are contacts 46 and 47, respectively. Contact 46 extends on each side of blade 41 and is adapted when moved toward blade 37 to engage a contact 48 aligned therewith and carried by blade 37.

From the foregoing it will be apparent that movement of cam 23 to the position in which it is shown in Figure 5, off position, rotates the elongated contact member 27 out of engagement with contacts 43, 44, 46, and 47, and permits these members to slidably engage the insulating member 26. Rotation of the cam 23 in a clockwise direction to low position, as shown in Figure 3, causes the leaf spring 28 to engage the lowermost dwell 27 and also causes the elongated contact member 27 to engage and raise the contacts 43 and 44 from the insulating member 26. Continued movement of the cam in a clockwise direction to high position moves the elongated contact 27 from beneath contacts 43 and 44 and into engagement with contacts 46 and 47. In this position, as shown in Figure 7, blades 41 and 42 are moved to the left and contact member 46 carried by blade 41 engages contact 48 carried by blade 37. In this position, contact member 43 is raised from the insulating member 26, but contact 44 may slidably engage said member.

Secured to the base 11 and extending upwardly to a point closely adjacent the supporting block 36 and blade connectors 37 and 38, from which it is insulated by member 51, is a resistor element 50 generally indicated by the reference numeral 52. The resistor 52 comprises a pair of windings 53 and 54 disposed in spaced parallel association. The windings 53 and 54 are maintained in parallel alignment by screws 56 extending longitudinally therethrough and engaging end members 57. Secured to the end members 57 at a point intermediate the windings 53 and 54 and extending parallel thereto is a nonconducting member 58. Secured to the end members 57 intermediate each winding and the non-conducting member 58 are conducting members or shorting bars 59 and 61. Slidably positioned on the conducting member 59 and having portions thereof slidably engaging the nonconducting member 58 and the resistance winding 53 are wipers 60 and 62. Two similar wipers 63 and 64 are likewise mounted on conducting member 61. The wipers 60, 62, 63, and 64 which provide electrical connections between resistance winding 53 and conducting member 59 and resistance winding 54 and conducting member 61, are adapted to be adjusted to selected positions and may then be secured by soldering or in any other suitable manner. The resistance windings 53 and 54 are also electrically

connected to blade connectors 38, 41, and 42 as will hereinafter be more fully disclosed.

The improved device of this invention is illustrated in Figure 8 in conjunction with an erecting or levelling system of a gyroscope. The schematic arrangement shown in Figure 8 is illustrative only, as the device may be employed in various other arrangements. The arrangement of mercury switches 65 and 66 and course solenoids 67 and 68 and range solenoids 71 and 72 is similar to the arrangement shown in my co-pending application, Serial No. 482,217, now Patent No. 2,417,573, issued March 18, 1947. In such an arrangement the mercury switch 65 is positioned and connected to energize solenoids 67 and 68 to correct deviation in course, and mercury switch 66 is positioned and connected to energize solenoids 71 and 72 to correct range deviation.

Operation

Operation of the improved control of this invention is as follows: assume for instance, that with the handle 17 in low position as shown in Figures 1 and 8, the mercury switch 65 rotates clockwise to engage electrodes 73 and 74, a circuit is then established as follows: from a source of supply to terminal 80, conductor 81, blade connector 37, contacts 43, 27, 44, blade connector 38, conductor 82, conductor 83, resistance 53, wiper 62, conductor 59, wiper 60, resistance 53, conductor 85, flexible conductor 86, conductor 87, solenoid 68, conductor 88, flexible conductor 89, electrode 74, mercury, electrode 73, conductor 90 to ground. If, in the meantime, mercury switch 66 also tilts, say clockwise, a parallel circuit is established as follows: from conductor 82 through a portion of resistance 54, wiper 63, conducting member 61, wiper 64, a portion of resistor 54, conductor 92, flexible conductor 93, conductor 94, solenoid 72, conductor 95, electrode 78, mercury, electrode 77, and conductor 96 to ground. In the event the mercury switches 65 and 66 are rotated in a counterclockwise direction, similar circuits are set up to the conductors 87 and 94. From this point the circuit including mercury switch 65, continues from conductor 87 through solenoid 67, conductor 97, flexible conductor 98, electrode 75, mercury, electrode 73, conductor 90 to ground. And in the case of mercury switch 66 the circuit continues from conductor 94 through solenoid 71, conductor 99, electrode 76, mercury, electrode 77, conductor 96 to ground. It is to be noted that circuits to a single mercury switch are alternative although parallel circuits to different switches may be established concurrently.

Assume now that the handle 17 is rotated clockwise to high position and that the mercury switches 65 and 66 are both rotated clockwise, a parallel circuit is established as follows: from terminal 80 through conductor 81, blade connector 37, contacts 48, 46, blade connector 41, conductor 100, conductor member 61, wiper 64, portion of resistor 54, conductor 92, flexible conductor 93, conductor 94, solenoid 72, conductor 95, electrode 78, mercury, electrode 77, conductor 96 to ground. Concurrently with the establishment of the above circuit, the other leg of the parallel circuit is energized and may be traced as follows: from contact 46, through contact 27, contact 47, blade connector 42, conductors 101 and 59, wiper 60, portion of resistance 53, conductor 85, flexible conductor 86, solenoid 68, conductor 88, flexible conductor 89, electrode 74, mercury, electrode 73, conductor 90 to ground. It is to be noted that this leg of the parallel circuit passes

through but a limited if any portion of the resistor 52. In the event mercury switches 65 and 66 are rotated counterclockwise, the legs of the parallel circuits from the conductors 87 and 94 are altered respectively as follows: conductor 87 through solenoid 67, conductor 97, flexible conductor 98, electrode 75, mercury, electrode 73, conductor 90 to ground. And from conductor 94 through solenoid 71, conductor 99, electrode 76, mercury, electrode 77, conductor 96, to ground. It is to be noted that the two circuits leading to either mercury switch 65 or 66 cannot be energized simultaneously, although either circuit leading through mercury switch 65 may be energized concurrently with either circuit leading through switch 66. In all circuits, the return is through ground connected to conductor 104 to the source.

It will be apparent from the foregoing that herein is provided a control for parallel circuits wherein each leg of the circuit may be controlled and adjusted independently or relative to the adjustment of the other leg. Moreover, the arrangement includes means whereby a second parallel circuit may be controlled through portions of the same resistor element used in controlling the first parallel circuit. Additionally, these parallel circuits may be adjusted relative to one another.

It will be apparent from the foregoing that the improved device of this invention when used in conjunction with two controlled elements may be so adjusted that the operation of one element is relative to the operation of the other element. For instance, when the device of this invention is employed for controlling a gyro erecting or levelling system that portion responsive to course deviation may be operated at a rate altogether different from the rate of operation of the range controlling portion. Likewise, each may be operated at a high or low rate in which the relative speed of each portion may be selectively altered.

It will also be apparent to those skilled in the art to which the improved device of this invention appertains, that numerous changes in design and construction may be made without departing from the spirit or scope of the invention. Accordingly, the patent granted hereon is not to be limited to the precise embodiment or illustration here disclosed or in any other manner except as may be necessitated by the terminology of the appended claims when given the range of equivalents to which they may be entitled.

I claim as my invention:

1. In a control: a resistance winding; a shorting bar; a plurality of contact members slidably mounted on said shorting bar for making movable connection with said winding; a multi-position switch; an input connection; an output connection; means connecting one end of said winding to said output connection; means, including said switch in one of its positions, for connecting said input connection to the other end of said winding; and means, including said switch in another of its said positions, for connecting said input connection to said shorting bar.

2. In a control: a pair of resistance members; an insulating member; and a pair of conductive members; means mounting said members in spaced, generally parallel relationship substantially in a common plane so that said insulating member lies between said resistance members and so that said conductive members lie between said insulating member and said resistance members; and resilient contacting members slidably along said conductive members, each said resil-

ient member comprising a portion for electrically connecting said resistance member and said conductive member and a portion for mechanically contacting said insulating member to maintain said resilient member in adjusted position along said conductive member.

3. In a control; a pair of resistance members, an insulating member, and a pair of conductive members; means mounting said members in spaced, generally parallel relationship substantially in a common plane so that said insulating member lies between said resistance members and so that said conductive members lie between said insulating member and said resistance members; resilient contacting members slidable along said conductive members, each said resilient member comprising a portion for electrically connecting said resistance member and said conductive member and a portion for mechanically contacting said insulating member to maintain said resilient member in adjusted position along said conductive member; and switching means connected to said resistance means and said conductive members for establishing a plurality of electrical circuits therethrough.

4. In a control, a switch having a plurality of contact making positions, a pair of resistance windings, means short circuiting any desired central portion of each of said windings, an input connection, a plurality of output connections, and means connecting said switch and said windings to provide a series circuit between said input connection and each of said output connections in each position of said switch, each said series circuit in a first position of said switch comprising both end portions of one of said windings, each said series circuit in a second position of said switch comprising one end portion only of one of said windings.

5. In a control, a switch having a plurality of contact making positions, a pair of resistance windings, a pair of slidable electrically connected contact means for making intermediate connection with each of said windings, an input connection, a plurality of output connections, and means connecting said switch and said windings to provide a series circuit between said input connection and each of said output connections in each position of said switch, said series circuits in a first position of said switch comprising portions of said windings and all of said contact means, said series circuits in a second position of said switch comprising portions of said windings and one contact means only of each of said pairs.

6. A rheostat for controlling the energization of an electrical device comprising an input conductor, an output conductor, a resistance wind-

ing, a pair of slidable members making contact with said winding to subdivide it electrically into a number of portions, switch means movable into either of a pair of operative positions, electrical connections through which movement of said switch into one of said portions completes a series electric circuit from said input terminal through said switch and portions of said winding to said output terminal and electrical connections through which movement of said switch into another of said positions completes a series circuit from said input terminal through said switch and one of said portions of said winding to said output terminal.

7. A rheostat comprising, in combination, switch means including two sets of fixed contacts and a member movable to complete an electric circuit between the contacts of either of said sets, an input conductor connected to one contact of each of said sets, a pair of elongated resistance windings, an elongated electrical conductor adjacent to said windings, a pair of contact members slidably connecting each of said windings with said elongated conductor to short circuit variable portions of said windings, an output conductor connected to one end of each said winding, and means connecting the remaining ends of said windings, and said elongated conductor respectively to the remaining contacts of said sets, so as to provide a circuit of adjustable resistance between said input conductor and one of said output conductors in each position of said movable member of said switch means.
